CLAIM

The ornamental design for a counter top vending unit, as shown and described.

DESCRIPTION

The single view disclosed is a top, front and side perspective view of a counter top vending unit showing my new design. The broken line showing of the counter top is for illustrative purposes only and forms no part of the claimed design. The left side view of the counter top vending unit and portions of the openings which are not visible on the single view shown, form no part of the claimed design.
